UNITED STATES PATENT OFFICE.

JAMES W. CONCHAR, OF DUBUQUE, IOWA.

PIPE-REGISTER.

SPECIFICATION forming part of Letters Patent No. 624,909, dated May 16, 1899.

Application filed August 23, 1898. Serial No. 689,364. (No model.)

To all whom it may concern:

Be it known that I, JAMES W. CONCHAR, a citizen of the United States, residing at Dubuque, in the county of Dubuque and State 5 of Iowa, have invented certain new and useful Improvements in Pipe-Registers; and I do hereby declare the following to be a full, clear, and exact description of the invention, such as will enable others skilled in the art to 10 which it appertains to make and use the same.

This invention relates to registers used in walls and ceilings to inclose a stove-pipe passing through a partition or floor; and the object of the invention is to so construct the 15 register as to admit of its being easily and quickly removed to clean it of dust settling in it or for any other purpose.

The nature of the invention will be fully disclosed in the description and claims following, reference being had to the accompanying drawings, in which—

Figure 1 is a plan view of the wall-plate which immediately incloses the pipe. Fig. 2 is a similar view of a ring to support the wall-plate. Fig. 3 is a central transverse section of the register complete as applied to a floor 25 and ceiling.

Similar letters of reference indicate corresponding parts.

30 In the ordinary construction of pipe-registers the floor-plate and wall-plate are connected in position by a drum of sheet metal attached to each by screws or bolts. It is thus a matter of considerable difficulty to remove 35 the register from its position and is sometimes necessary, since a great deal of dust will naturally settle in it in the course of a season, and the only practicable way of cleaning it thoroughly is to take it out. My 40 invention is designed to facilitate this operation by making the register separable, as will be described hereinafter.

Referring to the drawings, A designates a 45 wall-plate having the usual pipe-hole in the middle.

B is a ring the internal diameter of which is a little less than the external diameter of the wall-plate. This is provided on the back face, a short distance from the inner edge, 50 with an annular rib B', forming a seat for the wall-plate of proper diameter to receive the same and prevent lateral displacement. The

ring is also provided with suitable screw-holes B², by means of which it is attached to a wall or ceiling by screws, as shown. 55

The wall-plate A is provided with lugs A' on its upper or back side, and to these is secured the drum C in some suitable way, as by small bolts C'. The upper end of the drum is attached in the same way to a floor-plate 60 D, which may be of the customary form and construction.

It will be seen that on the removal of the pipe E it is possible to lift the drum and its connections off the supporting-ring attached 65 to the ceiling below, and thus convenient access may be had to all parts of the register for cleaning it and the like.

It will of course be understood that in fitting the register to a ceiling or wall a hole is 70 made therein somewhat larger than the wall-plate, but smaller than the outer diameter of the encircling ring or the plate attached to the other end of the drum. The construction of the register is such that this hole need not 75 be accurately formed, since the larger plate covers the top or floor side of the hole and the encircling ring covers it on the ceiling side. The annular rib B', within which the wall-plate fits neatly, prevents any lateral 80 movement of the plate D, which of course need not be fastened to the floor.

Having thus described my invention, what I claim as new, and desire to secure by Letters Patent, is—

1. In a pipe-register, the combination of a floor-plate adapted to cover the hole in the floor, a drum attached to said plate, a plate of smaller diameter attached to the other end of the drum, and a ring or border plate adapted to be attached to the ceiling and support the other parts, its internal diameter being less than the external diameter of the wall-plate, and its outer diameter corresponding 90 practically to that of the floor-plate, substantially as and for the purpose set forth. 95

2. In a pipe-register, the combination of a floor-plate having a central pipe-hole, a drum attached to its inner side, a wall-plate of smaller external diameter than the floor-plate, and having a suitable pipe-hole, attached to the other end of the drum, and an annular plate of less internal diameter than the external diameter of the wall-plate, with 100

an annular rib within which said wall-plate fits neatly, said annular plate being provided with screw-holes for attachment to the ceiling, and being adapted to close the hole in the 5 same and support the other parts of the register and prevent their accidental displacement, as described.

In testimony whereof I affix my signature in presence of two witnesses.

JAMES W. CONCHAR.
